UNITED STATES PATENT OFFICE.

GEORGE LANGLUMÉ AND EDWARD J. YBARZABAL, OF NEW ORLEANS, LOUISIANA.

MECHANICAL RACING COURSE.

Application filed November 29, 1922. Serial No. 604,026.

To all whom it may concern:

Be it known that we, GEORGE LANGLUMÉ and EDWARD J. YBARZABAL, citizens of the United States and residents of New Orleans, 5 in the parish of Orleans and State of Louisiana, have invented certain new and useful Improvements in Mechanical Racing Courses, of which the following is a specification.

10 This invention relates to amusement devices especially adapted for use as a source of amusement to young and old.

Briefly stated an important object of this invention is to provide an amusement device wherein a plurality of continuous rows 15 of mechanical horses are caused to travel in a given course to represent a horse race and thereby provide amusement to the onlookers and riders.

20 A further object is to provide novel means whereby the mechanical horses or figures are supported for movement in the prescribed course so that tipping over of the figures is prevented.

25 A further object is to provide a horse racing amusement apparatus which is of highly simplified construction, durable in use and cheap to manufacture.

Other objects and advantage of the 30 invention will be apparent during the course of the following description.

In the accompanying drawings, forming a part of this application and in which like numerals are employed to designate like 35 parts throughout the same,

Figure 1 is a plan view of the improved amusement apparatus.

Figure 2 is a side elevation of the same.

Figure 3 is a side elevation of one of the 40 horse supporting trailers or characters embodied in the invention.

Figure 4 is a vertical transverse sectional view taken on line 4-4 of Figure 3.

Figure 5 is a vertical transverse sectional 45 view taken on line 5-5 of Figure 3.

Figure 6 is a side elevation illustrating the operating truck and one of the carriages connected thereto, the operating truck and the carriage being in operative position on the tracks on which they operate.

Figure 7 is an end elevation of the power truck.

Figure 8 is a plan view of the power truck.

50 In the drawing wherein for the purpose

of illustration is shown a preferred embodiment of the invention, the numeral 5 designates a track having upstanding sides 6 which support the track or board in a raised position and within view of the 60 spectators. Of course in carrying out the invention, the track or board, the figures movable on the track and the other parts of the invention may be of any desired size.

Attention is invited to Figures 6, 7 and 8 65 which illustrate a truck 8 having axles 9 provided with wheels 10 mounted upon a pair of rails 11. Figure 8 plainly illustrates that an electric motor 14 is connected to the truck 8 and is connected to one of the 70 axles 9 through the medium of a train of gears 16. The electric motor 14 has connection with trolley wires 17 through the medium of trolley wheels 18 and arms or poles 19 pivoted to the truck 8 and acting 75 as a supporting means for the wheel. Of course any suitable means such as those now employed may be utilized to electrically connect the poles 19 to the electric motor so that the current is conducted from the 80 wires 17 to the motor for energizing the same.

In carrying out the invention each truck 8 is provided with a vertical standard 20 having a cross member 21, the terminal portions of which are forked as indicated at 22 and connected to the truck. One of the figures or horses is pivoted to the upper end of the standard 20 and the forward portion of the figure is pivoted to a pitman rod 90 24, the lower portion of which is connected to an extension 25 mounted upon the forward axle of the truck. It is thus seen that the figure or horse is pivoted to the apertured upper end portion of the standard 20 and that the forward portion has pivotal connection with the rod 24 so that when the truck is traveling along the tracks 11 the figure will be caused to rock or gallop.

Each truck 8 pulls a series of carriages 100 30 constructed in the manner illustrated in Figures 3, 4 and 5 wherein it shows that the carriages consist of channel beams 31 between which a supporting wheel 32 is arranged.

Each carriage 30 is provided with two wheels mounted upon a third rail 33 arranged between the parallel rails 11 and to hold carriage in position we have provided diverging arms 35 having their terminal 105 110

portions bifurcated to provide bearing members 36 between which rollers 37 are mounted. The track 5 is provided with depending guide members 40 with which the rollers 37 contact and it will be seen that the carriages cannot tilt as the result of centrifugal force.

Each carriage is provided with a rigid standard 42 having its lower portion forked 10 to provide attaching arms 43 connected to the upper side of the channel beam 31 and it will be observed that the standards 42 have braces 44 which are connected to the brackets or arms 35 of the rollers 37. The 15 upper portions of the standards 42 are formed with bearings 45 which rotatably receive pivot pins of the several figures 46 whereby the figures or horses are rotatably connected to the standards. That is to say 20 the intermediate portions of the figures are connected to the upper portion of the standards and the forward portions of the figures have pivotal connection with rods 48 joined at their lower ends to cranks 49 of the axles 25 of the carriages. Figure 5 plainly illustrates that the lower portion of the rod 48 is forked to provide arms 50 which straddle the I-beam and have pivotal connection with the cranks 49 as indicated at 52. It is thus 30 seen that as the carriage moves the figures connected thereto will be caused to rock or gallop in the manner of a horse.

In operation the electric motors are separately energized and the point of control may 35 be within the tower 53, corresponding to the judge's stand.

Of course in carrying out the invention the track is provided with slots 56 to receive the standards and the operating rods.

40 In use the riders of course mount the various mechanical horses and when the several electric motors are energized the continuous rows of mechanical horses will move. Of course the speed of the continuous rows of 45 mechanical horses may be varied by varying the supply of current. The particular means for holding the carriages and figures in position prevents the riders from being thrown from the horses. An amusement apparatus 50 constructed in accordance with this invention is extremely safe in use and may be made a source of profit to the operator and

a source of amusement to the riders as well as onlookers.

With reference to the foregoing description taken in connection with the accompanying drawings, it will be seen that an amusement apparatus constructed in accordance with this invention may be made of any desired size and may be employed as a 55 source of amusement for young and old. Furthermore, by reason of the construction employed the apparatus may be manufactured at an extremely low cost.

Having thus described the invention, what 60 is claimed is:—

1. A carriage for use on mechanical race tracks comprising a pair of channel beams, a pair of wheels rotatably mounted at the end portions of the beams, and adapted to 70 be mounted upon a single track, a standard having diverging attaching arms secured to said channel beams, a pair of brackets secured to said channel beams and having rollers adapted to engage guide members 75 whereby to hold the carriage in vertical position, and means whereby to brace said standard.

2. In a mechanical racing course, the combination of a board having a series of continuous slots, a carriage arranged beneath said slots, and having a pair of wheels, a single track upon which said wheels are mounted, a standard connected to said carriage and having means to pivotally support 80 a figure, a crank connected to one of said wheels, a rod connected to said crank and, to the figure mounted on the standard whereby to rock the figure, and means whereby to hold the carriage in position. 90

3. In a mechanical racing course, the combination of a board having slots, a carriage arranged beneath the board and having brackets, guiding means carried by said board and holding said brackets and carriage in an upright position, and a standard connected to said carriage and having means to pivotally support a figure, a crank having a rod connected to the figure, and wheels supporting the carriage, one of the wheels 100 having connection with said crank whereby to operate the same and rock the figure.

EDWARD J. YBARZABAL.
GEORGE LANGLUMÉ.
